GROUNDING ELECTRICAL POWER PLUG

Milton Morse, Bronx, N. Y.

Application November 24, 1954, Serial No. 33,236

Term of patent 14 years

(Cl. D26—1)

Fig. 1

Fig. 2

Fig. 3

Fig. 4

Figure 1 is a perspective view of a grounding electrical power plug showing my new design.

Figure 2 is a perspective view of the plug shown on Figure 1, as viewed from the rear thereof, and from below.

Figure 3 is a side elevational view.

Figure 4 is a bottom plan view.

I claim:

The ornamental design for a grounding electrical power plug, as shown.
